UNITED STATES PATENT OFFICE.

JAMES W. KNOBLOCK, OF ELMIRA, NEW YORK, ASSIGNOR TO AMERICAN LA FRANCE FIRE ENGINE CO., INC., OF ELMIRA, NEW YORK, A CORPORATION OF NEW YORK.

RESPIRATOR MASK.

1,410,927.

Specification of Letters Patent. Patented Mar. 28, 1922.

Application filed May 22, 1920. Serial No. 383,548.

To all whom it may concern:

Be it known that I, JAMES W. KNOBLOCK, a citizen of the United States, residing at Elmira, county of Chemung, and State of New York, have invented certain new and useful Improvements in Respirator Masks, of which the following is a specification.

The object of the present invention is to improve the construction and increase the efficiency of respirator masks whether of the sponge type or paper filter type. To this end the improved mask has been produced from a pressed sheet of metal, conformed as nearly as possible to the configuration of the human face to provide the least possible dead air or rebreathing space within the mask, and having relatively large eye pieces or windows and an air filter for purifying inflowing air. There is also a novel arrangement of air deflectors that divide the inflowing current of air into two streams that pass upwardly across the inner surfaces of the eyes or windows tending to maintain both faces of said eyes or windows at the same temperature, with a view to preventing nearly all fog or condensation of moisture. The mask is also provided with the usual inflatable soft rubber air cushion, which fits tightly against the wearer's face and an adjustable head gear for securely fastening the mask in place.

In order that the invention may be more fully understood it will first be described with reference to the accompanying drawings and afterward pointed out more particularly in the annexed claims.

In said drawings:

Fig. 1 is a front view of the improved respirator mask.

Fig. 2 is a rear or inside view of the same.

Fig. 3 is a vertical sectional view of the mask representing by dotted lines the position of the wearer's head when the mask is in use.

Fig. 4 is a transverse section view of the mask taken on the line 4—4 of Fig. 2.

Fig. 5 is a side elevation of the mask.

The improved mask is made up primarily of a sheet of metal, such as aluminum, indicated at 1, which is pressed into shape to conform as nearly as practicable to the contour of the human face, the mask plate 1 being of sufficient size to spread over the whole face and cover the mouth, nose and eyes of the wearer.

The careful shaping of the foundation mask plate 1 is important with a view to reducing to a minimum the dead air or rebreathing space within the mask.

The edge of the mask plate is entirely enclosed within an inflatable soft rubber cushion indicated at 5 of well known construction, but of improved shape to cooperate with the improved mask plate to accurately fit the face of the wearer and exclude the impure air and dust.

In the upper part of the shaped mask plate 1 are mounted the circular windows or eye pieces 10 of glass or non-inflammable celluloid, which are secured in suitable rims 11 that are permanently secured in proper openings formed in the mask plate. These windows are relatively large and by the shape of the mask plate are presented close to the face of the wearer so as to afford a wide range of vision.

Lower down, below and between the windows, the mask is formed with a slight outward protuberance 1^a to receive the nose and this protuberance has a flattened face which is centrally perforated to receive the flanged collar 15 of the filter box 16. This collar 15 is permanently attached to the projecting portion of the mask, and provides a relatively large air inlet passageway from the filter box 16. The filter box 16 may be of the sponge type, as shown in Figs. 1, 3 and 4, or it may be of the filter paper type such as indicated at 20 in Fig. 5. The respirator filter of both the sponge and filter paper types is preferably constructed as set forth in my copending application filed of even date herewith, Serial No. 383,549. Mounted within the shaped mask plate 1 and in the lower part thereof, is a shaped deflecting plate indicated at 25, secured in place by means of bolts 26 and nuts 27. This plate 25 has a central projection 25^a, which rests snugly against the inner surface of the projection 1^a of the mask plate, and from this point of contact with the inner surface of the mask plate, the deflector plate extends laterally in gentle curves toward the edge of the mask plate, these curved wings being bent outwardly away from the mask plate to form narrow air directing channels, which direct the inflowing currents of air upwardly across the inner surfaces of the window pieces 10. These curved side wings of the deflector plate are indicated at 25^b. The lower edge 110

of the deflector plate is bent inwardly to form a flange 25^c (indicated best in Fig. 3 of the drawings) to tightly contact with the inner surface of the mask plate 1.

5 It will be observed that the projection 25^a of the deflector 25 rests just above the air inlet 15 leading from the filter box 16 (or 20) with the result that the incoming current of air is divided into two streams as 10 indicated best in Fig. 4 of the drawings. These two streams pass upwardly beneath the curved side wings 25^b and sweep the inner surfaces of the eye plates to maintain an 15 equality of temperature over the inner and outer surfaces of the eye plates.

The operation of the device will be clear without further explanation. The breathing of the wearer causes air to pass inwardly and outwardly through the filter box, the 20 divided incoming current acting to prevent the fogging of the eye pieces as explained.

The improved mask is provided with some suitable head harness for fastening it in position upon the wearer. This harness as 25 shown comprises a strap 30 riveted at 31 to the upper part of the mask plate 1 and designed to pass over the crown of the head of the wearer. Adjustably secured to the head strap 30 by means of buckle 33 is the neck 30 strap 35 provided with eyelets 36 adjacent to the free ends, which are designed to slip over the studs or posts 37 which project forwardly from the bolts 26 above referred to. The neck strap is preferably provided with 35 elastic portions, such as indicated at 38, to firmly but yieldingly hold the mask in proper adjusted position upon the face of the wearer.

I claim:

40 1. A respirator mask comprising a sheet metal plate shaped to conform approximately to the contour of the human face, a forwardly projecting air filtering box mounted upon said shaped plate and having 45 free communication with the inner concave chamber thereof, eye windows mounted in said shaped plate above and on opposite sides of said filter box, and an air deflecting plate mounted within said shaped plate and 50 adapted to divide the incoming air into two currents and deflect the same over the inner surfaces of said eye windows, said deflecting plate engaging said shaped plate at its top central portion and at its outer edges 55 to form upwardly directed passageways.

2. A respirator mask comprising a sheet metal plate shaped to conform approximately to the contour of the human face and having a prominent forwardly projecting 60 nose, an air filtering box mounted upon said nose and having free communication therewith, eye windows mounted in said shaped plate above and on opposite sides of said nose, and an air deflecting plate mounted 65 within said shaped plate and adapted to

deflect the incoming air over the inner surfaces of said eye windows, said deflecting plate engaging said shaped plate at its top central portion and curving gently toward its edges which engage said shaped plate to 70 form upwardly directed passageways.

3. A respirator mask comprising a sheet metal plate shaped to conform approximately to the contour of the human face and having a prominent forwardly projecting 75 nose, an air filtering box mounted upon said nose and having free communication therewith, eye windows mounted in said shaped plate above and on opposite sides of said nose, an air deflecting plate mounted within 80 said shaped plate beneath said eye windows and formed with a central projection, which engages the inner surface of said nose above the opening leading from said filter box, said deflector plate forming 85 divided passageways for the incoming air to direct the air currents upwardly over the inner faces of said eye windows.

4. A respirator mask comprising a sheet metal plate shaped to conform approximately to the contour of the human face and having a prominent forwardly projecting 90 nose, an air filtering box mounted upon said nose and having free communication therewith, eye windows mounted in said shaped 95 plate above and on opposite sides of said nose, an air deflecting plate mounted within said shaped plate beneath said eye windows and formed with a central projection, which engages the inner surface of 100 said nose above the opening leading from said filter box, said deflector plate having laterally projecting curved wings that closely engage the inner face of the mask plate at their edges and form divided 105 passageways for the incoming air to direct the air currents upwardly over the inner faces of said eye windows.

5. A respirator mask comprising a sheet metal plate shaped to conform approximately to the contour of the human face and having a prominent forwardly projecting nose, an air filtering box mounted upon said nose and having free communication therewith, eye windows mounted in said shaped plate above and on opposite sides of said nose, an air deflecting plate mounted within 110 said shaped plate beneath said eye windows and formed with a central projection which engages the inner surface of said nose above 115 the opening leading from said filter box and having its lower edge flanged and its side edges and flanged lower edge so shaped as to make close contact with the inner face of said shaped plate and separated slightly 120 from the shaped plate between the nose and edges to form divided passageways for the incoming air to direct the air currents upwardly over the inner faces of said eye windows.

6. A respirator mask comprising a rigid sheet metal plate of sufficient size to completely cover the eyes, nose and mouth of the wearer and shaped to conform approximately to the contour of the human face and thereby reduce to a minimum the dead air or rebreathing space within the mask, eye windows mounted in proper position in said shaped mask plate, means for supplying 10 filtered air within said mask plate, a flanged deflector engaging said mask plate to form air passages, a cushion mounted upon said mask plate in position to closely engage the face of the wearer, the lower flanged edge of said deflector being disposed between said mask plate and cushion, and means for securing said mask in position upon the head of the wearer. 15

JAMES W. KNOBLOCK.
